[57] CLAIM

The ornamental design for a combined adjustable chair and ottoman unit, as shown and described.

DESCRIPTION

FIG. 1 is a front perspective view of a combined adjustable chair and ottoman unit showing my new design; FIG. 2 is a side perspective view, the opposite side being a mirror image thereof;

FIG. 3 is an alternate front perspective view;

FIG. 4 is a rear perspective view;

FIG. 5 is a side perspective view wherein the backrest has been pivoted to an alternate position; and

FIG. 6 is a top plan view thereof.
